UNITED STATES PATENT OFFICE.

THOMAS A. BELL, OF TRENTON, NEW JERSEY.

DESIGN FOR A SEGGER.

SPECIFICATION forming part of Design No. 19,126, dated June 4, 1889.

Application filed January 12, 1889. Serial No. 295,991. Term of patent 14 years.

To all whom it may concern:

Be it known that I, THOMAS A. BELL, a citizen of the United States, residing at Trenton, in the county of Mercer and State of New Jersey, have invented and produced a new and original Design for a Seggar, of which the following is a true and complete specification, reference being had to the accompanying drawings, forming a part thereof.

Figure 1 is a perspective view of a seggar showing my design, and Fig. 2 shows my design in plan.

My invention consists of a new, useful, and original shape or configuration for an article of manufacture—viz., a seggar.

The leading feature of my design or new shape for my article of manufacture is the

configuration produced by the combination of two or more right hexagonal prisms. In other words, my design for the seggar consists of a hollow right prismoid the exterior shape of which is that of combined hexagonal prisms.

I claim—

The design or shape for an article of manufacture—a seggar—the same consisting of a hollow right prismoid the exterior shape of which is that of combined hexagonal prisms, substantially as herein shown and described.

In witness whereof I have hereunto set my hand.

THOS. A. BELL.

Witnesses:
